DESIGN FOR A COMBINED PERFUME CONTAINER AND HOLDER

Mary S. Karoff, New York, N. Y.

Application March 6, 1942, Serial No. 106,095

Term of patent 3½ years

To all whom it may concern:

Be it known that I, Mary S. Karoff, a citizen of the United States and a resident of the city of New York, in the county of New York and State of New York, have invented a new, original, and ornamental Design for a Combined Perfume Container and Holder, of which the following is a specification, reference being had to the accompanying drawing, constituting a part thereof, in which:

Fig. 1 is a side elevational view of a combined

perfume container and holder showing my new design with the container partly withdrawn;

Fig. 2 is a similar view thereof with the container enclosed in its holder; and

Fig. 3 is an edge elevational view thereof taken from the right of Fig. 2.

I claim:

The ornamental design for a combined perfume container and holder, as shown.

MARY S. KAROFF.
